UNITED STATES PATENT OFFICE

170,140

TELEVISION CABINET

Samuel E. Adler, Chicago, Ill.

Application February 27, 1953, Serial No. 23,829

Term of patent 14 years

(Cl. D56—4)

To all whom it may concern:

Be it known that I, Samuel E. Adler, a citizen of the United States, residing at Chicago, in the county of Cook, State of Illinois, have invented a new, original, and ornamental Design for a Television Cabinet, of which the following is a specification, reference being had to the accompanying drawings, forming a part hereof.

Fig. 1 is a front elevational view of a television cabinet, showing my new design;

Fig. 2 is an elevational view of the right side thereof;

Fig. 3 is a sectional view indicated by line 3—3 of Fig. 1;

Fig. 4 is a sectional view indicated by line 4—4 of Fig. 1;

Fig. 5 is also a sectional view indicated by line 5—5 of Fig. 1; and

Fig. 6 is still another sectional view indicated by line 6—6 of Fig. 1.

The dominant features of my design reside in the portions shown by full lines of the drawings.

The left side of the cabinet resembles the right side and the back is plain.

I claim:

The ornamental design for a television cabinet, as shown and described.

SAMUEL E. ADLER.
